UNITED STATES PATENT OFFICE.

ELMER VICTOR ALLEN, OF HIAWATHA, KANSAS.

WASHING-MACHINE.

No. 866,612.

Specification of Letters Patent.

Patented Sept. 24, 1907.

Application filed January 2, 1906. Serial No. 294,288.

To all whom it may concern:

Be it known that I, ELMER VICTOR ALLEN, a citizen of the United States, residing at Hiawatha, in the county of Brown and State of Kansas, have invented 5 certain new and useful Improvements in Washing-Machines; and I do declare the following to be a full, clear, and exact description of the invention, such as will enable others skilled in the art to which it appertains to make and use the same, reference being had to 10 the accompanying drawings, and to the letters and figures of reference marked thereon, which form a part of this specification.

This invention relates to improvements in washing machines, including improvements on a machine for 15 which I obtained Letters Patent issued by the United States Patent Office under date of January 26, 1904 numbered 750,419 and I have as my object the production of a novel and simple device wherein the clothes are swung through the water, producing a rubbering, squeezing and suction action upon them without geared machinery and its consequent weight, noise in operation, expense and loss of motion.

The improvements consist chiefly in a simple elongated cup or hood, which causes the water to dash 25 upward and outward from the forward side, and downward and outward from the rear side of the cup which cup is attached to an agitator of simpler construction than that covered by said Letters Patent No. 750,419 and which is provided with an adjustable hand grip to 30 enable the operator to shorten or lengthen his leverage while operating the machine. I attain these objects by the mechanism illustrated in the accompanying drawings, in which,—

Figure 1 is a vertical section of the interior of the 35 machine, upheld by a combined frame and support. Fig. 2 is a top view of a tank and cup, the top of the tank and rod and grip omitted. Fig. 3 is a detail of the cup and agitator. Fig. 4 is a top view of the device, with its lid closed in position in a combined frame 40 and stool; Fig. 5 is a side view of agitator with grip and vacuum cup removed and Fig. 6 is a detail of one of the looped feet of the machine.

Similar letters refer to similar parts in the several views.

45 In these figures A represents the box or tank of the machine, B the top thereof, and C C the handles.

D D are stop plates, E E radiating rub bars, spaced slightly above or resting upon the bottom of the machine. These bars as well as corner-posts P P—may be 50 omitted in the construction of the machine, if preferred.

H H are legs and H' H' cross pieces, the legs and

cross pieces constituting a stool to support the tank, and when reversed, as shown in Fig. 4, forming a frame or crate for shipping or storing the machine. The 55 tops of the legs are mortised forming seats h h in which the tank is held securely.

I is an agitator rod provided at its lower end with two oppositely extended arms I' I'.

J is a cup of elongated shape, rigidly fastened to the 60 lower end of said rod I, as shown in Figs. 1 and 3. Said agitator I and its projecting arms are formed of a single rod the lower bent end of the rod forming one arm which extends beyond the bottom of the cup at one end thence it extends slightly above the top 65 of and within said end of the cup, and along the bottom to the center thereof, thence to and out of the opposite end of the cup and around to the point of beginning forming the other arm. In its course this extension of the rod hugs the bottom of the cup both inside and outside as well as the inside of the ends of the cup, rigidly but, as shown in Figs. 1, 2 and 3, on the outside of the cup it is spaced from the ends thereof forming loops upon which the clothes most soiled may be hung, or into which spaces they may be held in 70 order that they may be brought into the full force of the current of water that is deflected from the sides of the cup in its rotary motion besides holding the clothes in a position where they will be squeezed against the stop plates and more thoroughly cleansed. The front of 75

the agitator is that part of the elongated cup which is forced against the water in its rotary motion by the power at the handle of said rod; either side of said cup may be the front it depending on the direction in which the power is applied; only one half of either 80

side of the cup can at any time be the front, but the other half is front on reverse motion. J' is a saddle carried by rod I at the bottom of cup J and riveted thereto. The upper end of said rod is bent forming 85 handle K. This handle is provided with hand grip K' which is made adjustable on handle K, as shown by dotted lines in Fig. 1, to enable the operator to shorten or lengthen the strokes of the handle in operating said agitator rods. R is a stop flange on said handle and L is a faucet. As shown in Fig. 1 this faucet is 90

placed in the side of the tank close to the bottom, and as the metal sides of the tank, instead of the bottom edge being turned upward around the sides, all the water can be readily drained out of the bottom of the tank through said faucet. Said sides of the tank being 95

turned underneath in the form of loops O O—they serve as seams to elevate the tank slightly above the floor when it is removed from its combined stool and 100 crate.

What I claim and desire to secure by Letters Patent
is—

In a washing machine the combination with a vertical
agitator rod, of a saddle thereon, an elongated inverted
5 cup, oval at the mouth, narrowing towards the bottom,
and held rigidly within said saddle, and the two arms
formed by the lower end of said rod projected around,
within and without, both bottom and ends of said elong-

gated cup, back to point of contact with said rod, substantially as set forth and shown.

In testimony whereof, I affix my signature, in presence
of two witnesses.

ELMER VICTOR ALLEN.
